UNITED STATES PATENT OFFICE.

JOHN A. HOLZAPFEL, OF JACKSON, MICHIGAN.

ANCHOR.

Application filed October 31, 1922. Serial No. 598,118.

To all whom it may concern:

Be it known that I, JOHN A. HOLZAPFEL, a citizen of the United States, residing in the city and county of Jackson, State of Michigan, have invented certain new and useful Improvements in Anchors, of which the following is a specification.

This invention relates to improvements in anchors.

10 The main objects of the invention are:

First, to provide an improved anchor which is particularly adapted for use on row boats or fishing boats, and is effective in holding on lake and river beds of different character.

15 Second, to provide an improved anchor which has large holding capacity in proportion to its size and weight.

Further objects, and objects pertaining to 20 structural details will definitely appear from the detailed description to follow.

I accomplish the objects of my invention by the devices and means described in the following specification. The invention is 25 clearly defined and pointed out in the claims.

A structure which is a preferred embodiment of the invention is clearly illustrated in the accompanying drawing forming a part of this application, in which:

30 Fig. I is a perspective view of my improved anchor mounted upon a boat, the boat being shown in connection therewith in order to illustrate certain advantages of 35 the anchor.

Fig. II is a side elevation of my improved anchor with the grapple or head partly in section, the grapple being shown in its 40 normal position by full lines, its possible movement on the body of the anchor being indicated by dotted lines.

45 Fig. III is a top plan view of the grapple or head member of my improved anchor.

In the drawings similar numerals of 50 reference refer to similar parts in all of the views.

Referring to the drawing my improved anchor comprises a shaft-like shank 1 tapered upwardly and terminating in a point 2 for the attachment of the anchor rope or cable. At its lower end the shank 1 is provided with an annular shoulder 3 and below this a conical or pointed tip 4.

55 The anchor head or grapple member comprises the annular hub 5 having radially disposed blade-like arms 6 integral there-

with. The outer ends 7 of these arms are preferably tapered and the arms are provided with longitudinal flanges 8, the arms being curved upwardly so that they are 60 scoop-like in form. I preferably provide holes 9 at the inner ends of the arms through which the water may flow as the anchor is raised, thus washing off any mud that may have been picked up when the 65 anchor was raised from the bed.

The grapple member is mounted upon the shank member for rotative and longitudinal movement thereon, being adapted to normally rest upon the shoulder or stop 3. 70

In use, when the anchor is dropped to the bed of a lake or stream, the pointed end of the shank will embed in the bed of the lake or stream but should a lateral pull occur the blade-like arms engage in the bed of the stream or lake the grapple adjusting itself on the shank according to the depth to which the shank is embedded and according to the surface upon which the anchor is resting. 75

In Fig. I, I illustrate my improved anchor as suspended from the prow of a boat 10, a pulley designated generally by the numeral 11 being provided for the anchor rope 12. When the anchor is hauled up the arms of the grapple will straddle the prow of the boat the ends of the arms swinging the grapple to one side should the arms engage. This allows the anchor to hang substantially perpendicular at the 80 prow of the boat and the boat is not injured by the anchor scraping or the arms engaging therewith. 85

While my improved anchor is especially 90 designed by me for use on small boats and launches, it is adapted for use in various relations. The parts of my improved anchor are very economical to produce and assemble, and it has very large holding power in proportion to its size and weight. 95

Having thus described my invention what I claim as new and desire to secure by Letters Patent is:

1. An anchor comprising an upwardly tapered shank having a shoulder at its lower end and a conical tip below the shoulder, and a grapple member loosely mounted on said shank for rotative and longitudinal movement thereon and adapted to normally rest on said shoulder, said grapple member comprising an annular hub portion with radially disposed upwardly 105 110

2 curved blade-like arms tapered at their outer ends and having upwardly projecting flanges on their longitudinal edges and holes at their bases.

- 5 2. An anchor comprising an elongated shank having a stop at its lower end and a grapple member comprising an annular hub portion and radially disposed upwardly curved blade-like arms tapered at their outer ends and having upwardly projecting flanges on their longitudinal edges, said arms having holes at their bases and being substantially spaced, said grapple member being loosely mounted on said shank for rotative and longitudinal movement thereon and adapted to normally rest on said shoulder.
- 10 3. An anchor comprising an upwardly tapered shank having a shoulder at its lower end and a conical tip below the shoulder, and a grapple member having radially disposed blade-like arms loosely

25 mounted on said shank for rotative and longitudinal movement thereon and adapted to normally rest on said shoulder.

4. An anchor comprising an elongated shank having a stop at its lower end, and a grapple member loosely mounted on said shank for longitudinal and rotative movement thereon and adapted to normally rest on said stop, the bore of said grapple member being of such diameter as to permit tilting of the grapple member while resting on said stop, said grapple member having substantially spaced radially disposed blade-like arms tapered at their outer ends.

30 35 In witness whereof, I have hereunto set my hand and seal in the presence of two witnesses.

JOHN A. HOLZAPFEL. [L. s.]
